METHOD OF AND APPARATUS FOR MOUNTING SHEET MATERIAL ON A FLAT SUPPORT FOR PRINTING OR OTHER PURPOSES

John Sylvester Wheelwright, Tonbridge, and
George Henry Abell, Esher, England; said Abell
assignor to said WheelwrightApplication November 29, 1933, Serial No. 700,336
In Great Britain December 10, 1932

21 Claims. (Cl. 101—407)

This invention provides an improved method for mounting sheet material, for instance fabric, on a flat support for printing or other purposes. The invention is particularly concerned with 5 that method of printing known as stencil or screen printing, wherein stencils formed of permeable material are employed. In such printing it is essential that the material to be printed shall be held evenly and firmly on the support, 10 and the primary object of the invention is to provide means whereby this can be ensured.

With this object in view the invention provides in its broadest aspect a method of mounting sheet material (for example fabric) on a flat support for printing or other purposes, which comprises 15 (a) providing the support and one side of the sheet material each with a waterproof surface, (b) damping one of said waterproof surfaces, and (c) laying the sheet material on the support with 20 its waterproof surface opposed to the waterproof surface of the support to which it then adheres by suction.

The waterproof surface on the sheet material may be provided in any convenient manner but 25 is preferably formed by uniting that material by means of an adhesive to a layer of rubber or other waterproof material.

The invention also includes in printing apparatus, a printing bed having a waterproof surface 30 to permit sheet material provided on one side also with a waterproof surface to be mounted on the printing bed by the method described above.

The support upon which the sheet material is mounted to be printed or otherwise operated on 35 may be wholly stationary or may comprise a travelling conveyor (for example an endless belt) of rubber or other waterproof material which forms the upper face of the support and which carries the sheet material past the printing or 40 other devices for operating upon it.

The invention may be carried out by means of apparatus of widely different forms depending to 45 some extent upon the nature of the printing or other operation to be performed on the sheet material. In order that the invention may be clearly understood two forms of apparatus suitable for carrying out the invention when the sheet material is to be printed by the stencil or screen printing method will now be described, by 50 way of example, with reference to the accompanying drawings which are more or less diagrammatic.

In the drawings:

55 Figure 1 shows in sectional elevation the front

end of one form of apparatus according to the invention;

Figure 1a is a similar view of the rear end of the apparatus;

Figure 2 is a plan of the part of the apparatus 5 shown in Figure 1;

Figure 2a is a plan of the part of the apparatus shown in Figure 1a;

Figure 3 is a section on the line 3—3 of Figure 1 drawn to an enlarged scale;

Figure 4 is a section on the line 4—4 of Figure 1a but drawn to a larger scale;

Figure 5 is a sectional elevation of a modification of the right-hand end of the apparatus, as seen in Figure 1 but drawn to a larger scale;

Figure 6 is a sectional elevation of a machine 15 for forming a roll of the aforesaid laminated sheet material;

Figure 7 is a side elevation of a device for laying 20 said laminated sheet material on to the support; and

Figure 8 is an end elevation of the device shown in Figure 7.

Like reference numerals indicate like parts 25 throughout.

Referring first to the construction shown in Figures 1 to 4 inclusive, the apparatus comprises a main frame 10 carrying a table 11 over which travels in contact therewith an endless rubber conveyor belt 12, the table being lubricated to 30 reduce friction. This belt passes around drums 13, 14, arranged one at each end of the table and rotatably mounted in bearings on the main frame. The lower stretch of the conveyor belt is supported by a number of rollers 15. The drum 35 14 is arranged to be driven from an electric motor 16, the driving shaft of which is operatively connected to a shaft 17 carrying a bevel wheel 18 which meshes with a bevel wheel 19 on a shaft 20. Mounted on the latter shaft is a worm 21 which 40 gears with a worm wheel 22 on the shaft 23 of the drum 14. The said shaft is operatively connected to that drum by a magnetic clutch 24 which is controlled by a switch 25. Thus the conveyor belt 12 can be intermittently driven by 45 actuating the switch 25 and this can be effected, in accordance with requirements, by means of any convenient part of the printing mechanism or by a device associated therewith. The means for intermittently driving the conveyor belt 12, 50 however, forms no part of the present invention. It will be appreciated that the table 11 and the rubber conveyor belt 12 together constitute the support aforesaid on which the material to be printed is laid and that the said belt provides the 55

waterproof surface on the upper face of the support.

The material 26 to be printed is a fabric, a roll 27 of which is rotatably mounted at the front end 5 of the main frame. The web of fabric is led from the roll 27 between tensioning rails 28 to a calender comprising a heated drum 29 and a pressing roller 30 which is mounted so as to permit it to be adjusted towards and away from the drum 10 29. Both the drums 29 and the roller 30 are mounted so as to be free to rotate. The fabric 26 is united to a blanket 31 of rubber or other waterproof material which is fed simultaneously into the calender. The blanket 31 passes from 15 the drum 29 over the conveyor belt 12, thence around guide rollers 32, 33 and 34 at the back end of the main frame and back to the drum 29 through a tensioning and straightening device 35 and around guide rollers 36, 37. Adhesive is applied to the outer face of the blanket 31 before it 20 enters the calender by means of a roller 38 which dips into a trough 39 containing the adhesive. The fabric 26 is fed on to that face of the blanket 31 which has been coated with adhesive and by 25 means of the pressing roller 30 is firmly united to the blanket. The laminated web thus formed is fed fabric upwards on to the front end of the conveyor belt 12 to the outer face of which a film of water has been previously applied by means of 30 a roller 40 which dips into a bath of water 41. Thus the waterproof underside of the laminated web as it is fed on to the moistened face of the conveyor belt 12 will be caused to adhere to said belt by suction and will be carried thereby past 35 the printing mechanism which is not shown as it forms no part of this invention.

After the fabric has been printed, it is separated from the waterproof blanket 31 and led over rotatable card wheels 42 which feed the web of fabric forwards to a drying device. In practice, a short length of the printed fabric will first be separated from the blanket 31 by hand and laid on said card wheels after which the latter will grip the fabric and feed it forwards while simultaneously separating it from the blanket. The card wheels 42 are fixed to a shaft 43 which is arranged to be driven through a manually controllable differential device by means of a sprocket 44 and a chain 65 which passes around sprockets on the shaft 23 of the drum 14 and on the shaft of the guide roller 33. This differential device permits the tension of the fabric as it is separated from its base to be adjusted at will and is shown in detail in Figure 4. The sprocket 44 is fixed to the casing 80 of the differential device. Pinions 81, 82 are journaled in said casing and the crown wheel 83 is keyed to the shaft 43. The other crown wheel 84 is free to rotate on the shaft 43 and is secured to a worm wheel 85 which is also free to rotate on said shaft. The worm wheel 85 meshes with a worm 86 on a spindle 87 which is provided with a hand wheel 88 whereby it can be rotated. The worm wheel 85 and worm 86 are mounted in a casing 89 which is bolted to the main frame 10. By rotating the worm 86 by means of the hand wheel 88 the tension of the fabric may be adjusted as desired either while the machine is stationary or while it is in motion.

Between the guide roller 34 and the tensioning and straightening device 35, the waterproof blanket 31 passes a cleaning device whereby any colouring substance which may have penetrated the fabric 26 during printing is removed from the blanket. The said cleaning device may be of any convenient form. As shown on the drawings it

comprises a trough 45 containing a number of water-spraying devices 46 to which water can be supplied from a valve-controlled pipe 47, and a number of rotatable scrubbers 48 arranged to be rotated from the shaft 17.

The invention is primarily intended to be used in association with stencil or screen printing mechanism whereby designs each comprising several different colours can be printed repeatedly along the length of the fabric or other sheet material. In such printing it is essential that there shall be no transverse movement of the fabric during printing as otherwise the various designs or parts of each design will not be in correct registration. In order to prevent any transverse deflection of the fabric 26 as it travels through the apparatus, means is provided for guiding the conveyor belt 12 to which the fabric is held by suction as described above. The means shown on the drawings for this purpose consists of a number of rollers 51 which are mounted along one margin of the conveyor belt and are arranged to travel along a guide-way 52 in the table 11 and to be guided in peripheral recesses 53 in the drums 13, 14. 25

In the construction shown in Figures 1 to 4 an endless blanket 31 is provided but, if desired, a non-continuous blanket may be employed as shown in Figure 5. In this modification, the blanket is led from a roll 54 between tensioning rails 55 over the adhesive-applying roller 38 to the calender wherein the fabric 26 is united thereto in the manner described above. The return stretch of the fabric after passing over the guide roller 36 and partly around the heated drum 29 is led around a guide roller 56 and is rewound into a roll 57 on a beam driven by a belt 58 from a pulley on the shaft of the drum 13. This arrangement of the blanket 31 is preferred when that blanket is made of waterproof paper or other cheap substance which when once used can be destroyed. In that case it will be unnecessary to provide any cleaning devices such as the water-sprays 46 and the scrubbers 48 for the blanket. 4

Instead of laying the laminated material 26, 31 on to the conveyor belt 12 to be carried thereby past the printing mechanism, said laminated material may be laid on a stationary printing bed in which case stencils or screens will be moved 5 step by step along the printing bed. This modification of the invention may be carried out by means of the apparatus shown in Figures 6, 7 and 8. The web of fabric from the roll 29 is united to the waterproof blanket 31, coming from the roll 54, in the calender as described with reference to Figure 5. The laminated material 26, 31 thus formed after passing over the heated drum 29 is wound into a roll 59 on a spindle or beam 60 which is driven by a chain or belt 61 from the drum 29. The latter can be driven from any convenient shaft, for instance a shaft such as is indicated at 49 by means of gearing 50 and a chain or belt 62.

The roll 59 of laminated material is then 61 mounted on a carriage 63 arranged to travel on rails 64 provided one along each side of the printing bed. The laminated material is unwound from the roll 59 on the carriage 63 with the fabric 26 uppermost and passes beneath tension- 70 ing rails 66 and thence over a roller 67 which dips into a trough 68 containing water. Thus the roller 67 applies a film of water to the underside of the waterproof blanket 31, and from said roller the laminated material is led fabric upwards on 75

to the printing bed which is formed by the table 11 on which a blanket 33 is laid with a waterproof sheet 10, for example an oil cloth, on top of the blanket. A soft roller 11 is provided on the carriage 63 for pressing the laminated material on to the waterproof sheet 10 to which it adheres by suction in a perfectly flat condition.

5 After printing, the fabric 26 may be torn from the waterproof blanket 31 and be conveyed to another apparatus for further treatment if necessary while the waterproof blanket 31 may in turn be removed from the printing bed leaving the waterproof sheet 10 clean and ready without any further attention for the next application 10 of laminated material. The blanket 31 may then be washed and dried, if necessary, and wound on to a beam in readiness for using again in the apparatus shown in Figure 6.

15 It is to be understood that the waterproof blanket to which the material, for example fabric, to be printed is united may be of any convenient form. For instance, it may be a waterproof material such as rubber or a material for example paper which has been treated so as to 20 render it waterproof on one or both sides.

25 Further, it will be appreciated that the invention is not restricted to the specific lay-out shown on the drawings as obviously that may be modified to suit different requirements.

30 We claim:

1. A method of mounting sheet material on a flat support to be subsequently operated upon, which comprises providing the support and one side of the sheet material each with a waterproof surface, damping one of said waterproof surfaces, and laying the sheet material on the support with its waterproof surface opposed to the waterproof surface of the support.

2. A method of mounting sheet material on a flat support to be subsequently operated upon, which comprises providing the support with a waterproof surface, uniting the sheet material by means of an adhesive to a layer of waterproof material so as to provide a waterproof surface 45 on one side of the sheet material, damping one of said waterproof surfaces, and laying the sheet material on the support with its waterproof surface opposed to the waterproof surface of the support.

50 3. A method of mounting fabric to be printed on a printing bed, which comprises the steps of providing the printing bed with a rubber surface, uniting the fabric to a layer of rubber so as to form a laminated sheet having a rubber surface on one side, damping one of said rubber surfaces, and feeding the laminated sheet with its rubber face downwards on to the rubber surface on the printing bed.

55 4. In a printing apparatus, means for mounting sheet material on a flat support having a waterproof surface, comprising means for providing the sheet material on one side with a waterproof surface, means for damping one of said waterproof surfaces, and means for feeding the sheet material with its waterproof surface downwards on to the waterproof surface of the support.

60 5. In a printing apparatus, means for mounting sheet material on a support having a waterproof surface, comprising means for forming a laminated sheet by uniting the sheet material by an adhesive to a layer of waterproof material so as to provide a waterproof surface on 65 the underside of said sheet material, means for

damping one of the two waterproof surfaces, and means for feeding the laminated sheet material with its waterproof side downwards on to the waterproof face of the support.

6. In a printing apparatus, means for mounting sheet material, comprising a movable conveyor belt of waterproof material which provides a waterproof surface on to which the sheet material is to be laid, means for providing the sheet material on one side with a waterproof surface, 10 means for damping one of said waterproof surfaces, and means for feeding the sheet material with its waterproof face downwards on to one end of the belt.

15 7. In a printing apparatus, means for mounting sheet material on a flat support having a waterproof surface on which the sheet material is to be laid, comprising a calender for uniting the sheet material in web form to a rubber base also in web form so as to provide a waterproof 20 surface on one side of the sheet material, means for feeding simultaneously the rubber base and the sheet material into said calender, means for applying adhesive to the rubber base before it meets the sheet material, means for applying a 25 film of water to one of said waterproof surfaces, and means for feeding the sheet material with its waterproof face downwards on to the waterproof surface of the support.

30 8. In a printing apparatus, means for mounting sheet material, comprising a movable rubber belt which provides a waterproof surface on which the sheet material is to be laid, means for providing the sheet material with a waterproof base, means for feeding the sheet material with 35 its waterproof base downwards on to one end of the movable belt, means for damping the outer face of the belt before the sheet material is laid thereon, and means at the other end of the belt for separating the sheet material from its waterproof base.

35 9. In a printing apparatus, means for mounting sheet material, comprising a movable belt having a waterproof surface on to which the sheet material is to be laid, means for providing the 45 sheet material on one side with a waterproof base, means for feeding the sheet material with its waterproof base downwards on to one end of the movable belt, means for damping the upper face of the belt before the sheet material is laid 50 thereon, and a card wheel at the other end of the belt for separating the sheet material from its base.

40 10. In a printing apparatus, means for mounting sheet material in web form for printing purposes, comprising a printing table, a movable belt having a waterproof surface on to which the sheet material is to be laid, which belt travels over said table, means for uniting the sheet material by adhesive to a base of waterproof material in web form so as to provide a waterproof surface on one side thereof, means for damping one of said waterproof surfaces, means for feeding the sheet material with its waterproof base downwards on to said movable belt at one end, 60 means at the other end of said movable belt for separating the sheet material from said base, and means for cleaning said waterproof base after it has been separated from the sheet material.

45 11. In a printing apparatus, means for mounting sheet material for printing purposes, comprising a printing table, a movable rubber conveyor belt which travels over said table, means for damping the outer face of said belt, a calendering device, means for feeding simultaneously 70

- into said calendering device a web of fabric to be printed and a web of rubber, means for applying adhesive to the rubber web before it is fed into the calendering device to be united to the fabric, 5 which calendering device is arranged to feed the laminated material thus formed with its rubber side downwards on to the belt at one end, at least one rotatable card wheel at the other end of the movable belt for separating the fabric from the 10 rubber, a trough containing a number of water-sprays and scrubbing devices, and means for conveying the rubber past said sprays and scrubbing devices to be thereby cleaned after separation from the fabric.
15. 12. In a printing apparatus, means for mounting sheet material, comprising a movable conveyor or having a waterproof upper surface on to which the sheet material is to be laid, means for providing the sheet material on one side with a base 20 having a waterproof surface, means for damping one of said waterproof surfaces, means for feeding the sheet material with its waterproof surface downwards on to one end of the conveyor, means at the other end of the conveyor for separating the sheet material from its base, and means for adjusting the tension of the sheet material as it is being separated from the base.
13. In a printing apparatus, means for mounting sheet material, comprising a movable support 30 having a flat waterproof upper surface on which the sheet material is to be laid, means for providing the sheet material with a base having a waterproof surface on its underside, means for damping one of said waterproof surfaces, means 35 for feeding the sheet material with the waterproof face of the base downwards on to the waterproof surface of the support at one end, a rotatable card wheel situated at the other end of the movable support for separating the sheet material from its base, and means for adjusting the tension of the sheet material as it is being separated from said base, which tension-adjusting means is a manually operable differential device which is operatively connected to the card 40 wheel.
45. 14. In the art of printing upon sheet material, a method of mounting the material to be printed on a printing bed, which comprises the steps of providing a layer of waterproof material on the printing bed, uniting a layer of waterproof material to one side of the material to be printed, damping one of said waterproof surfaces, and laying the sheet material with its waterproof side downwards on the waterproof layer on the printing bed.
50. 15. In the art of printing upon webs, the method of mounting a web to be printed on a traveling conveyor of waterproof material whereby it is carried over a printing bed past printing devices, which comprises the steps of providing a layer of waterproof material on one side of the web, damping the surface of the conveyor on which the web is to be laid, and feeding the web 55 with its waterproof layer downwards on to the damped surface of the conveyor.
16. A method of mounting sheet material on a traveling conveyor having a waterproof surface, which comprises the steps of providing the sheet material with a waterproof surface, bringing the waterproof surfaces of the conveyor and the sheet material together, and damping one of the waterproof surfaces prior to bringing the surfaces together, whereby the waterproof surfaces are temporarily united by suction. 60
17. Apparatus for printing upon a fabric comprising a conveyor having a waterproof surface, a waterproof carrier web onto which the fabric to be printed upon is secured, means for feeding the carrier web onto the conveyor in such manner that the waterproof surfaces come into contact, and means for damping one of the waterproof surfaces. 65
18. In printing apparatus, means for mounting sheet material in the form of a laminated web, consisting of two united webs of material onto a conveyor having a waterproof upper surface by adhesion, of which webs one has a waterproof surface on its outer side, and the other is printable material, means for damping one of said waterproof surfaces, means for feeding the laminated web with its waterproof surface downwards onto the waterproof surface of the conveyor at one end, means at the other end of the conveyor for separating the two webs, and means for adjusting the tension of one web as it is separated from the other. 70
19. In a printing apparatus, the combination with a printing bed and means for printing upon sheet material, of a waterproof carrier web onto which the fabric to be printed upon is secured, a traveling conveyor by which the carrier web is carried past the printing means, which conveyor has a waterproof surface thereon, means for feeding the carrier web onto the conveyor so that the waterproof surfaces of the carrier web and the conveyor come into contact, and means for damping one of the waterproof surfaces. 75
20. In the method of printing upon a fabric with a temporary waterproof layer, applying the backed fabric to a supporting member provided with a waterproof surface, moistening the surfaces of said supporting member and waterproof backing of the fabric respectively and pressing said supporting member and fabric into surface contact. 80
21. A method of mounting flexible sheet material having on one side a waterproof surface on a flexible support having a waterproof surface which comprises the steps of damping one of said waterproof surfaces and progressively pressing the sheet material on to the support with its waterproof surface opposed to the waterproof surface of the support to bring said surfaces into contact with exclusion of air. 85
